UNITED STATES PATENT OFFICE.

WILLIAM P. KELLOGG, OF TROY, NEW YORK.

DESIGN FOR A CURRY-COMB.

SPECIFICATION forming part of Design No. 15,954, dated March 10, 1885.

Application filed October 30, 1884. Term of patent 14 years.

To all whom it may concern:

Be it known that I, WILLIAM P. KELLOGG, of Troy, in the county of Rensselaer and State of New York, have invented and produced a new and original Design for Curry-Combs, of which the following is a specification, reference being had to the accompanying drawings, forming part thereof, in which drawings—

Figure 1 represents a plan view of my comb; 10 and Fig. 2 represents a back view of the comb, showing the arrangement of bars, &c.

In the drawings, A represents the main frame of the comb, to which are attached the comb-bars extending transversely thereto. 15 The upper portion of the frame is provided on each side with projections or knockers F. The comb-bars are of uniform length, and the ends of upper one, which comes at the upper and narrowest part of the frame, are situated behind the knockers or projections F, which extend beyond the edge of the main frame. The general contour of the comb-frame is that of a horseshoe, the ends of which are connected by a bar, C, having an integral part, c, to provide for the attachment of the handle. 25

The cross-bar C and that part of the horseshoe-shaped frame opposite thereto are connected by the portion E, which is of a form to resemble the head, shoulders, and front legs 30 of a horse. At the point of juncture of the

upper portion of this part E and the frame the horse's head, which is situated at the upper part of the connecting-piece E, appears projecting through an opening in the frame.

The frame is provided at intervals throughout its length with openings in the form of horseshoes, which gives the frame a very aesthetic appearance. 35

I claim—

1. The herein described design for curry-combs, the same consisting of the frame in the form and configuration of a horseshoe, ornamented by a representation of a horse's head, neck, and front legs, and comb-bars of uniform length extending across said frame, as 40 shown.

2. The herein-described design for curry-combs, the same consisting of the frame in the form and configuration of a horseshoe, and having openings in the form of horseshoes 45 throughout its length, and ornamented by a representation of a horse's head, neck, and front legs, and comb-bars of uniform length extending across said frame, as shown. 50

In testimony whereof I have set my hand in 55 the presence of two subscribing witnesses.

WM. P. KELLOGG.
